US00D360615S

United States Patent [19]

Sakashita et al.

[11] Patent Number: Des. 360,615

[45] Date of Patent: ** Jul. 25, 1995

[54] **SMALL ELECTRIC MOTOR WITH MOUNTING FLANGE**

[75] Inventors: Hiroshi Sakashita; Yukio Fukuda; Jun Yamashita, all of Nagano, Japan

[73] Assignee: Sankyo Seiki Mfg., Ltd., Nagano, Japan

[**] Term: 14 Years

[21] Appl. No.: 17,073

[22] Filed: Jan. 3, 1994

[30] Foreign Application Priority Data

Aug. 19, 1993 [JP] Japan 5-25056

[57] CLAIM

The ornamental design for a small electrical motor with mounting flange, as shown and described.

DESCRIPTION

FIG. 1 is a top perspective view of a first embodiment of the electrical motor showing our new design; FIG. 2 is a top view of the FIG. 1 embodiment; FIG. 3 is a side view of the FIG. 1 embodiment; FIG. 4 is a side view taken orthogonal to the FIG. 3 view of the FIG. 1 embodiment;

FIG. 5 is a bottom plan view of the FIG. 1 embodiment; FIG. 6 is a top perspective view of a second embodiment of the electrical motor showing our new design; FIG. 7 is a top view of the FIG. 6 embodiment; FIG. 8 is a side view of the FIG. 6 embodiment; FIG. 9 is a side view taken orthogonal to the FIG. 8 view of the FIG. 6 embodiment; and, FIG. 10 is a bottom plan view of the FIG. 9 embodiment.

FIG. 1

FIG. 2

FIG. 3

FIG. 4

FIG. 5

FIG. 6

FIG. 7

FIG. 8

FIG. 9

FIG. 10
